(57) **CLAIM**

The ornamental design for a gun magazine tube as shown and described.

DESCRIPTION

FIG. 1 is a front perspective view of a gun magazine tube, showing my design;

FIG. 2 is a rear perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The broken lines shown in all views illustrate portions of the gun magazine tube that form no part of the claimed design.

1 Claim, 8 Drawing Sheets

FIG. 1
